UNITED STATES PATENT OFFICE.

MESROPE DAVID, ZAKAR DAVID, HARRY DAVID, AND PAUL DAVID, OF BROCKTON, MASSACHUSETTS.

DESIGN FOR A LIMB-CUTTER OR BRANCH-TRIMMER AND HATCHET.

SPECIFICATION forming part of Design No. 35,720, dated February 11, 1902.

Application filed December 11, 1901. Serial No. 85,498. Term of patent 14 years.

To all whom it may concern:

Be it known that we, MESROPE DAVID, ZAKAR DAVID, HARRY DAVID, and PAUL DAVID, citizens of Turkey, (but having applied for 5 citizenship of the United States,) residing at Brockton, in the county of Plymouth and State of Massachusetts, have invented and produced a new and original Design for a Limb-Cutter or Branch-Trimmer and Hatchet; and we do 10 hereby declare the following to be a full, clear, and exact description of the same, reference being had to the accompanying drawing, forming a part thereof.

In the drawing is an elevation showing our 15 design.

As shown in the drawing, the leading or material features of our invention consist of a sweeping curved or arched portion *a*, having a knife-edge for the limb-cutter or branch-20 trimmer, and said curved portion merging into substantially a sharp straight part (indicated at *b*) and toward the shank or stock of the implement, the lower end of this stock being connected to a handle *d*. The body or

blade of this trimmer or cutter is also arched 25 or curved, as shown at *c*, and this curve at its point *f* meets the cutting edge *a*, and from such point the blade gradually widens, as seen at *c* and *e*, until it meets at *g* the base of the hatchet *h*, *i* being the hatchet edge. The 30 hatchet, the limb-cutter, and the stock are made, as shown, in a single piece.

Having described our invention, what we claim as new, and desire to cover by Letters Patent, is—

The design for a limb-cutter or branch-trimmer, and hatchet, as herein shown and described.

In testimony whereof we affix our signatures in presence of two witnesses.

MESROPE DAVID.
ZAKAR DAVID.
HARRY DAVID.
PAUL DAVID.
